(Cl. D2—238)

FIG. I.

FIG.2.

FIG. 1 is a front perspective view of a bathing cap showing my new design, the dash dot lines representing the dividing line between a plain band which is applied along the edge of the cap and the remainder of the cap; and

FIG. 2 is a rear perspective view thereof.

The essential features of my design reside in the full line disclosure on the drawing.

I claim:

The ornamental design for a bathing hat, substantially as shown and described.
